UNITED STATES PATENT OFFICE.

JOSEPHINE A. GREATHOUSE, OF LOS ANGELES, CALIFORNIA.

DESIGN FOR A LAMP.

Application filed January 23, 1928. Serial No. 24,997. Term of patent 3½ years.

To all whom it may concern:

Be it known that I, JOSEPHINE A. GREATHOUSE, a citizen of the United States, residing in Los Angeles, in the county of Los Angeles and State of California, have invented a new, original, and ornamental Design for Lamps, of which the following is a specification, reference being had to the accompanying drawings, forming part thereof.

Figs. 1 and 2 are front and side perspective views of a lamp embodying my design.

I claim:

The ornamental design for a lamp substantially as shown.

JOSEPHINE A. GREATHOUSE.
